UNITED STATES PATENT OFFICE

EDWARD R. HEWITT, OF MIDVALE, NEW JERSEY, ASSIGNOR TO INTERNATIONAL MOTOR COMPANY, OF NEW YORK, N. Y., A CORPORATION OF DELAWARE

VENTURI COMBUSTION CHAMBER FOR INTERNAL-COMBUSTION ENGINES

Application filed June 28, 1927. Serial No. 202,060.

In internal combustion engine design a result much striven for is the complete elimination of unburned, or partially burned particles of fuel due to insufficient air or lack of 5 homogeneity of the mixture of fuel and air such that portions of the fuel do not receive sufficient air to support a sudden and complete burning. Every particle of fuel must avail itself of sufficient air to support its 10 combustion as distinct from adjacent particles and the more highly atomized the fuel the more efficient will be the explosion. Where the volumes of fuel are finely atomized and mixed intimately with suitable volumes 15 of air, the resulting operation approaches a maximum efficiency and such result is highly desirable in all types of engines.

Although applicable to other forms of internal combustion engines, the present invention will be described in connection with a 20 Diesel engine, an object of the invention being to provide a design which will produce a highly vaporized mixture by causing great turbulence of the injected fuel in the vicinity 25 of the air supplied for its combustion whereby the particles of fuel are broken up into a finely divided state. More specifically, the invention has for an object to provide a Venturi chamber in the head of the cylinder, the 30 relation between the configuration of the chamber, the size and shape of the Venturi nozzle, the size of the throat, and the character of the injection of the fuel being such that 35 a great turbulence of the vapor results and a highly intimate mixture is effected. After the first combustion has taken place this gives a double mixture of burning gases.

Although a Venturi chamber, per se is known to be old, no design has yet proposed, 40 nor does one suggest to establish a definite relationship between the above elements constituting the injection and mixing apparatus and the present invention, recognizing the characteristics of, and supplying the required 45 relationship of elements, establishes an advance over known structures resulting in greatly improved operation.

Further objects and advantages will appear as the description proceeds and reference will now be had to the accompanying

drawings forming a part hereof for a more detailed description of the invention, wherein:

Figure 1 is an elevation, in section, showing a cylinder head construction in which the 55 present invention has been embodied.

Figure 2 is a section taken through the fitting shown in Figure 1.

Figure 3 is a front elevation of the fitting shown in Figure 2. 60

Figure 4 is a rear elevation of the fitting shown in Figure 2.

Figure 5 is a diagrammatical illustration of the relationship existing between the throat, outlet flare and internal flare of the 65 venturi at the bottom of the combustion chamber.

Referring to the drawings, *a* indicates a head construction for the cylinder of an internal combustion engine provided with suitable water channels *a'* to cool the parts when operating. Secured at the top of the head is an injector *b* which injects a conical spray of fuel *b'* into the combustion chamber referred to later. The lower extremity of the head *a* 70 is provided with an internally threaded portion which receives a fitting *c*. This fitting is formed with a hollow internal portion having a throat *c'*, an outlet flare *c*² and a spherical portion *c*³. Suitable recesses *c*⁴ are provided 80 in the fitting to receive a spanner wrench and enable the fitting to be screwed into place. Cavities *c*⁵ co-operate with certain of the channels *a'* to enable the cooling fluid to be circulated around the Venturi throat *c'*. 85 The head *a* has a centrally hollowed portion *a*², the upper walls *a*³ of which are conical. These walls are designed so that their sides lie generally parallel to the outer portions of the conical spray from the injector *b* and they 90 are further formed to maintain an air space *a*⁵ between the walls and such outer portions of the spray. The hollow portion *a*² co-operates with the spherical portion *c*² of the fitting *b* to form a combustion chamber *a*⁴ of 95 generally bulbular shape. By maintaining an air space around the spray in this manner, the latter will entrain the air and promote the intimacy of the mixture between the fuel spray and the air which supports its combus-

100

tion. It will be apparent that the spray finally strikes the spherical portion c^3 of the fitting c and the baffling effect of this lower portion of the combustion chamber a^4 results in great turbulence within such chamber and a thoroughly mixed volume of fuel and air. At the bottom of the combustion chamber a^4 the throat c' of the fitting c permits the exhaust of the thoroughly mixed volume of fuel into the cylinder and the outlet flare c^2 from the venturi in connection with the difference in pressure existing between the two sides thereof, results in a great velocity and turbulence of the fuel upon entering the cylinder. The differential pressure existing between opposite sides of the venturi should be such that the velocity of such incoming fuel is approximately 500 feet per second, a value which should be a minimum for efficient operation. For adiabatic flow of gas, the velocity is, of course, dependent only on the respective areas of the inlet and the Venturi throat, and on the relative pressures.

The total volume of the combustion chamber a^4 is designed to equal, approximately, one fifteenth of the swept volume of the cylinder, this relationship giving the best values of compression and resulting velocity through the Venturi throat c' . The cylinder block is indicated at f and a sleeve valve e . This construction is particularly advantageous in view of the fact that the venturi construction occupies considerable room and prevents overhead valves from being used.

It has been found that the most desirable relationship between the length (height or altitude) and diameter of the Venturi throat the outlet flare, and the entrance flare, should be as follows. The length should equal the diameter of the venturi, the length of the outlet flare from the center of the venturi should equal three times the diameter of the venturi, the length from the center of the venturi of the entrance flare should equal 2.85 times the diameter of the venturi, and the width of the entrance to the throat should be twice the diameter of the venturi. In addition to these values, the angle between the walls of the outlet flare and the center line of the Venturi throat, should be 8° . These values are illustrated in Figure 5 of the drawings, wherein a diagrammatic illustration of the construction is given.

What I claim is:

1. As an article of manufacture, a nozzle for introducing gases to an engine cylinder, said nozzle having a passage therethrough comprising a Venturi throat in the form of a cylinder whose altitude is approximately equal to its diameter, an inlet flare leading to the throat, and an outlet flare on the other side of the throat.

2. The combination as claimed in claim 1 wherein the inlet flare has walls lying in arcs having radii equal to 2.85 times the diameter

of the throat and struck from points in the median plane of the throat, the throat and flared out portion being aligned.

3. The combination as claimed in claim 1 wherein the diameter of the entrance flare at its end distant from the throat is approximately twice the diameter of the throat. 70

4. The combination as claimed in claim 1 wherein the distance from the median plane of the throat to the end of the outlet flare is 75 approximately three times the diameter of the throat.

This specification signed this 16 day of June A. D. 1927.
